ROLL HOLDER AND WEB FEEDER

Kurt Rudolf Schneider, Bainbridge, N.Y., assignor to Eureka Specialty Printing Company, Scranton, Pa., a corporation of Pennsylvania

Filed May 14, 1958, Ser. No. 735,186

16 Claims. (Cl. 242—75.3)

This invention relates to the art of strip feeding, and more particularly to the withdrawal of the strip from a supply such as a roll, and intermittent delivery of the strip to a point of employment.

An object of the invention is the provision of a strip feeding apparatus including a turning device mounted so that it moves toward the outlet point for the strip during traction on the strip and thereby reduces the length of the portion of the strip between the supply and outlet points, together with means for moving the roller away from the outlet when the traction is reduced below a predetermined value.

Another object is the provision of strip feeding apparatus including parts for controlling the delivery of the strip from a supply roll and its movement into an intermittently operating strip converting device, and parts for preventing retrograde movement of the delivery end of the strip.

A further object is the provision of strip feeding apparatus in which the free rotation of a roll of the strip material is restricted and in which the strip is delivered to an intermittently operating strip converting device, with the strip acting to procure varying retarding effects upon its movement toward such device.

A further feature is the provision of a strip feeding apparatus including a support pivot for receiving a roll of strip material, a removable end structure for the pivot including a friction head for engaging the roll, a member for engaging the pivot, and a spring active between the friction head and the member to hold the member engaged with the pivot and the friction head engaged with the roll.

With these and other objects in view, as will appear in the course of the following description and claims, an illustrative form of practice of the invention is shown on the accompanying drawings, in which:

Fig. 1 is a top elevation of the illustrative form, shown attached to a device for employment of the strip.

Fig. 2 is an end elevation thereof.

Fig. 3 is a section substantially on the broken line 3—3 of Fig. 2.

Fig. 4 is an elevation of a sleeve member, substantially on line 4—4 of Fig. 3, at a larger scale.

Fig. 5 is an axial section, substantially on line 5—5 of Fig. 4.

Fig. 6 is a view corresponding to a part of Fig. 2, with parts omitted or conventionalized.

In the drawings, the strip feeding apparatus is illustratively attached to a device D, shown fragmentarily and which may be a label applying machine as shown in the Schneider Patent 2,754,022, wherewith the strip S comprises a succession of labels which are to be intermittently advanced, as by a reciprocating shuttle H which engages in apertures 10 of the strip S, and thereby advances the strip by one label distance during a cycle of operation of the device D, for the severing and application of a label to an article. Thus at each feeding movement of the shuttle H, traction is exerted upon the strip; and during the return movement of the shuttle H, the strip may be at a standstill without traction thereon from the shuttle H.

The illustrative apparatus has a support comprising the pad 11 which is secured to the device D, and an arm 12 extending from the pad 11 and having fixed thereon a pivot 13. An antifriction bearing 14 (Fig. 3) on the pivot 13 supports a disk 15 having fixed thereto a rocker piece 16 which in the illustrative form has its center of mass below the pivot axis so that the rocker can gravitationally assume a position of rest. The piece 16 has an arcuate extension 17 illustratively concentric with the pivot axis, and presenting a bottom surface for frictional engagement by the strip S as will be described hereinafter. The piece 16 also has fixed thereon, eccentric to the pivot axis, a shaft 18 with antifriction bearings 19 for mounting a strip turning roller 20, illustratively having the end flanges 21 for guiding the strip.

A pin 22 on the rocker piece 16 engages one end of a coil spring 23 which is attached at its other end to a pin 24 on the arm 12. When the rocker is at rest, the pin 22 is in the illustrative practice above the radial line from the pin 24 to the axis of pivot 13 wherewith the rest position of the rocker is slightly counterclockwise (Fig. 2) of its purely gravitational rest position, due to the balancing of the efforts of the spring and gravity; and the spring is stretched to a greater and greater extent as the rocker is moved clockwise (Fig. 2).

An outlet guide roller 25 is rotatably mounted on a shaft 26 fixed on the arm 12; and the upper part of its surface is positioned to deliver the strip to the device D for engagement by the shuttle H thereof. Spaced from the outlet roller 25 is a round pin 27 which passes through an arcuate slot 28 in the fixed arm 12, the arc being illustratively concentric with the indicated position of the axis of a second shaft 29 fixed to the arm 12 between the surfaces of the roller 25 and the pin 27. The pin 27 can be fixed in a selected position along this arc by a nut 30. A detaining roller 31 has a central bore larger than the second shaft 29 so that this roller 31 may assume various positions relative to this pin: the outer diameter is greater than the distance between the surfaces of the roller 25 and the pin 27, and the axis of the roller 31 is located relatively above the plane through the axes of the roller 25 and the pin 27 so that it is drawn by gravity into the nip between these parts. In practice it is preferred to form the roller 31 of two sections which can rotate and move relative to one another, and which each have an outer friction surface, for example provided by a roughened rubber jacket. The rollers 25, 31 may be held on their respective mounts by removable flange pieces 33 secured to the outer ends of the mounting shafts 26, 29. In the illustrated structure, the rollers 25 and 31 are located substantially at the horizontal plane through the axis of the pivot 13, with the pin 27 below this plane. It is preferred to provide a slot 34 in the arm 12 so that the position of the second shaft 29 may also be adjusted when thicker or thinner strip stock of greater or lesser flexibility is being employed.

The pivot 13 extends over the arcuate extension 17 and has antifriction bearings 35 for supporting a rotatable sleeve 36 upon which a roll R, providing a supply of the strip material S, may be placed with one end surface bearing against an end flange 37 of the sleeve 36. The outer bearing 35 is held in place by a split ring 38. The projecting outer end of the pivot 13 has a transverse pin 39 with rounded ends.

The roll R is held on the sleeve 36, and pressed against the flange 37, by a friction head 40 having an end surface for engaging the roll R. This friction head 40 is hollow and receives a sleeve 41, which fits around the end of the pivot 13 and has an inwardly extending flange 42b to provide an internal recess 42 with axial access grooves 42a (Fig. 4) extending through the end flange 42b (Fig. 3), for receiving and detaining the ends of the pivot pin

39, therewith providing a bayonet joint or connection in which the parts can be slid axially or telescoped, and then rotated about their common axis into a position at which they cannot be separated by direct axial movement. A radial hole or bore 46 is drilled through the sleeve 41 so that (Fig. 5) it provides grooves in the inner surface of the flange 42b for receiving the ends of the pin 39. As shown in Fig. 4, the axial planes through the notches 42a and through the bore 46 are preferably at right angles. At its outer end, the head 40 has an enlarged bore for receiving the end of a compression coil spring 43 which bears at its other end against the knob 44 which is secured to the sleeve 41 by a screw 45.

For operation, with the head 40 and associated parts removed from the pivot 13, a roll R of the strip material is placed on the sleeve 36. The head 40 is then engaged over the end of the pivot 13 so that the pivot enters the sleeve 41, this sleeve being rotated by its knob 44 if necessary for alinement of the open ends of grooves 42a with the pivot pin 39. The knob 44 is pressed inward, against the spring 43, until the pin 39 passes beyond the end flange 42b of the sleeve, and the knob can then be rotated so that the ends of pivot pin 39 pass into the recess 42: upon release of the knob 44 after a rotation of 90 degrees, the spring presses the knob 44 and the sleeve 41 outward so that the ends of the pin 39 are held seated in the grooves provided by the cross bore 46, with reaction against the friction head 40 so that the latter applies a friction effort against the roll R and in turn the roll R is pressed against the flange 37 whereby the strip is located and accurately positioned for feeding. This friction effect exists by slippage of the spring 43 in its seat or by slippage of the head 40 against the roll R.

The strip S withdrawn from the roll R is then threaded in the apparatus by passing it over the turning roll 20, then reversing its direction and passing it beneath the friction surface of the arcuate extension 17, and bringing it to the rollers 25, 31. The roller 31 can be lifted by a finger, and the strip S passed between the rollers 25, 31, and its end moved into the device D, for example beneath a top guide plate 60, so that the strip S can be engaged and intermittently fed by the shuttle H of the device D. The roller 31 is now released, so that it bears against pin 27, and presses the strip S toward the roller 25.

The device D can now be energized, so that its shuttle H reciprocates. During each leftward movement of the shuttle H (Fig. 2), traction is exerted along the strip S, and a portion thereof is advanced from the outlet roller 25 of the feeding apparatus and delivered to the device D. This traction acts to lift the roller 31 slightly by movement along the surface of pin 27, noting that the strip engages with an arc on the surface of the roller 31 (Fig. 2), and then with an arc on the surface of the roller 25: and the strip S is thus freed for the advancement toward the device D. This traction effect is continued along the strip S to the turning roller 20. If the strip S is loose between roller 20 and the outlet roller 25, this traction reduces the loose loop then existing, until the strip S is drawn against the friction surface of the extension 17: during this time, the traction effect does not cause withdrawal of further strip material from the roll R nor provoke a rotation of the roll R, nor a movement of the rocker structure. When the strip has been brought to engagement with the braking extension 17, traction effect along the strip S causes the strip to pull the extension 17 and therewith other parts of the rocker member with it. The turning roll 20 is therewith moved toward the outlet roller 25, and acts as a pulley over which the strip moves to shorten the loop existing from the supply roll R to the turning roller 20 and back to the extension 17, wherewith the strip is permitted to slide along the extension 17 by a distance about equal to the movement of the extension 17, so that the movement of 17 is about half the movement of the strip into the device D. Thus there is a yielding under the effect of the traction; and each reciprocation of the shuttle H, with intermittent

feeding of the strip, is not accompanied by an arcuate movement of the roll R to deliver the necessary amount of strip material.

A full roll R has a significant mass. While at rest, if the traction effect along the strip S acts directly to start the roll R in rotation, the sudden effort may tear the strip, particularly if shuttle-engaged perforations or other weakening is present. When the roll R has been started in rotation, it may continue by its momentum, and a major amount of the material may be unwound and become tangled. With the arrangement of the invention, the sudden pull by the shuttle H upon the strip S is not directly transmitted to the roll R, but the rocker piece 16 with its turning roller 20 moves with the strip S, so that a lesser force is exerted upon the roll R. The amount of this force is automatically adjusted, by the illustrated apparatus, in that the movement of the turning roller 20 occurs with movement of the rocker piece 16 against gravity and spring action, so that the sudden pull of the shuttle is converted to a gradually increasing force whereby the strip S slowly starts the roll R. That is, when the traction force is low, the strip S can slip along the extension 17 without compelling rocking through a large arc: and when the traction force is greater, the engagement of the strip and extension is tighter, and the piece 16 moves through a greater arc. When the shuttle H slows down, toward the end of its stroke, the traction along the strip drops in amount, so that the rocker piece 16 and the roller 17 no longer move toward the outlet roller 25, but a lesser continued traction is present; the rocker piece tends to return by gravity and spring action, slipping along the strip S; thus moving the roller 20 farther from the roller 25, and therewith continuing to draw strip material from the roll R and continuing the slow rotation of the roll R for that purpose. Thus, the rapid reciprocations of the shuttle H do not demand the delivery of the full amount of strip material from roll R during the feeding stroke, but this amount can be supplied over the entire course of the shuttle cycle of feeding and return strokes.

Further, friction head 40 acts to restrict free rotation of the roll R. A full roll R has a large external diameter, so that it is moved through a small arc at each feeding demand: as the roll R approaches depletion, it has a smaller diameter, and is turned through a greater arc for each demand. With a device D operating at a fixed number of cycles per minute, the averaged rotational speed of a fresh roll R is low but with relatively high inertia and momentum effects for the averaged speed; and the averaged rotational speed of a depleted roll is high but with low inertia and momentum effects at such speed. The head 40 acts with an essentially constant retarding effect upon the roll, significantly less than the traction effect along the strip until the roll diameter is less than that of the head 40: so that its restricting action is relatively low at the low rotational speed of a full roll whereby the traction is largely employed for moving the roll, and becomes relatively higher as the roll decreases in diameter and inertia and momentum effects and increases in rotational speed. When the final few turns remain in the roll, the head 40 presents a less and less surface to the roll, noting that at this time the smaller radius of gyration connotes a lesser momentum and also a lesser length of strip material to be delivered for a given angular movement of the roll.

When the traction along the strip, from the shuttle H, is high, slippage of the strip along the surface of the extension 17 is reduced and may cease, so that the rocker piece 16 is pulled through a greater angle for an intermittent shuttle action; and thereupon the spring 23 acts to assist gravity in resisting the movement of the rocker piece 16 and to return it when the traction ceases.

When the traction from the shuttle H drops, the detaining roller 31 moves downward by gravity in the illustra-

tive device and therewith grips the strip S against the outlet roller 25, and is itself held against rotation by its engagement with the pin 27. Thus, the part of the strip S opposite the shuttle H and downstreamward of the outlet roller 25 comes to a standstill, awaiting a further feeding by the shuttle; whereas the part of the strip S upstreamward of the outlet roller 25 is moved slightly by the detaining engagement of the roller 31, but remains essentially without movement for the part engageable by the extension 17 and to the position occupied by the turning roller 20 at the end of the feeding movement. The part of the strip S downstreamward of the extension 17, as far as the rollers 31, 25, increases in relative length as the rocker piece 16 and the roller 20 return by a counterclockwise movement (Fig. 2) after the shuttle traction has ceased due to the strip portion which moves around the roller 20. In the illustrative form, with the supply roll R mounted on the pivot 13 concentric with the path of movement of the roller 20, the length of the strip portion between the roll R and the roller 20 changes but slightly at each feeding, due to the small decrease in diameter of the roll R and therewith the small change in the length of the common tangent line from the roll R to the roller 20. Therewith, if the roll R continues to rotate even after the rocker piece 16 and roller 20 have returned to original position, this is restricted by the head 40 so that only a small looseness or looping can develop, which is taken up during the succeeding feeding stroke or strokes of the shuttle, before there is the aforesaid gradual further demand upon the roll R.

It will be understood that the illustrated practice is not restrictive; and that the invention may be employed in many ways within the scope of the appended claims.

What is claimed is:

1. A strip feeding apparatus comprising a frame, a rocker structure pivoted on the frame and including a rocker member and a strip turning roller journaled to move with the rocker member, an outlet guide for the strip, a support for a strip supply from which the strip may be led to and around the turning roller and thence to the outlet guide, a friction portion on the rocker member whereby movement of the strip past the outlet guide causes the rocker member to move in the direction of the strip, and means for returning the rocker structure.

2. A strip feeding apparatus as in claim 1, in which the friction portion provides a surface over which the strip may slide and located between the turning roller and the outlet guide.

3. A strip feeding apparatus as in claim 1, in which the returning means includes a spring connected to the frame and to the rocker structure.

4. A strip feeding apparatus as in claim 3, in which the rocker structure has its center of gravity below its pivotal support on the frame.

5. A strip feeding apparatus comprising a support, a pivot and an outlet guide on the support, a rocker member on said pivot, said pivot being adapted to receive a roll of the strip material, and a roller eccentrically mounted on the rocker member, said rocker member having a brake surface for engagement by the strip; the apparatus being adapted for movement of the strip from the roll to the roller, around the roller and thence to the brake surface and to the outlet guide.

6. A strip feeding apparatus as in claim 5, in which the brake surface is an arcuate area concentric with said pivot.

7. A strip feeding apparatus as in claim 5, in which the rocker member is suspended on said pivot and the brake surface is located on the rocker member so that it is below the said pivot when the rocker is gravitationally at rest.

8. A strip feeding apparatus comprising a support, a rocker member pivoted on the support, a strip supply on the support, a strip turning roller mounted on the

rocker member to move therewith, an outlet guide roller on the support, the apparatus being adapted for movement of the strip to and around the turning roller and thence along the surface of the rocker member and thence to the outlet guide roller whereby the strip can move the rocker member in one direction, means for returning the rocker member, and a strip detaining device for engagement by the strip at a portion thereof between the turning and outlet rollers for preventing retrograde movement of the strip.

9. A strip feeding apparatus as in claim 8, in which the strip detaining device is mounted on the support for being moved against gravity from detaining position during tension along the strip from a part thereof adjacent said outlet guide roller therewith the strip is shifted toward a plane which is tangent to the outlet roller and to the turning roller, and for gravitational movement upon cessation of such tension toward its detaining position and therewith shifting the strip away from the said plane whereby to increase the length of the strip portion between the said rollers.

10. A strip feeding apparatus as in claim 8, in which the detaining device is a roller mounted on the support for movement toward and from the outlet roller.

11. A strip feeding apparatus as in claim 8, in which the detaining device comprises a pin mounted on the support spaced from and essentially parallel to the outlet roller, and a friction roller resting against the pin and movable along the surface thereof between a position in which it binds the strip against the outlet roller and a position in which the strip can move between the outlet and friction rollers.

12. A strip feeding apparatus comprising a support, a pivot and an outlet guide on the support, a strip supply roll on the pivot, a rocker member on the pivot for gravitationally assuming a rest position, said rocker member having a friction surface for engagement by the strip, a turning roller mounted on the rocker member eccentrically to the pivot at a point upstreamward of the brake surface, an outlet guide on the support downstreamward of the friction surface, said rocker being movable against gravity by the strip engagement with the friction surface upon withdrawing traction on the strip whereby the length of the portion of the strip from the roll to the outlet guide is reduced, and a spring active for urging return movement of the rocker member after the said rocker member has been moved from its gravitational rest position.

13. A strip feeding apparatus comprising a rocker member having a strip turning device thereon, an outlet guide for the strip, a strip supply from which the strip is led to and around the said strip turning device, and a friction surface portion on the rocker for engaging the strip on its way to the outlet guide.

14. A strip feeding apparatus for feeding a strip to a mechanism including an intermittently acting device for pulling the strip, comprising a frame, a pivot on the frame for supporting a roll of the strip material, braking means for restricting the rotation of the roll about the pivot axis, a rocker member having a bearing portion engaged with the pivot, said rocker member having an arcuate extension fixed thereon and providing a friction surface movable therewith on a path radially outside the said roll, a turning roller journaled on the rocker member for movement therewith on a path radially outside the said roll, whereby the strip may be threaded from the roll to said turning roller and then to engagement with said friction surface and then to the pulling device therewith the delivery movement of the strip in response to the pulling device and the engagement of the strip with said friction surface causes the rocker member to move in the direction of the strip movement toward said outlet guide, means to prevent retrograde movement of the strip, and means for returning the rocker member during an idle period of the pulling device, the braking

effort of said roll braking means being less than the effort of said returning means after a major movement of said rocker member with the strip.

15. A strip feeding apparatus for feeding a strip to a mechanism including an intermittently acting device for pulling the strip, comprising a frame, a pivot projecting from the frame for supporting a roll of the strip material, braking means for restricting the rotation of the roll about the pivot axis, a rocker member having a bearing portion engaged with the pivot between the frame and the roll location whereby the pivot has a free end so that the roll can be slid axially onto and off from the pivot, said rocker member having an arcuate extension fixed thereon and movable therewith in a path about the said pivot, said arcuate extension having a friction surface for engagement with the strip, said arcuate extension having a free edge, a pivot shaft projecting from the rocker member parallel to said pivot and eccentric relative thereto, a turning roller journaled on the pivot shaft for movement with the rocker member and having a free end, whereby the strip may be threaded over said free ends from the roll to and around said turning roller and then to engagement with said friction surface and then to the intermittently acting device and wherewith the delivery movement of the intermittently acting device upon the part of the strip engaged with said friction surface causes the rocker member to move in the direction

10

5

of the strip movement toward said intermittently acting device, means located between the said friction surface and said intermittently acting device to prevent retrograde movement of the strip, and means for returning the rocker member during an idle period of the intermittently acting device.

16. A strip feeding apparatus comprising a support, a rocker member pivotally mounted on the support for rocking movement upon engagement by the strip when fed, a strip turning roller journaled to move with the rocker member, an outlet guide for the strip, a strip supply mounted on the support from which the strip is led to and around the said roller, a friction surface portion on the rocker for engaging the strip between said roller and said outlet guide whereby the strip can move the rocker member in one direction, and means to return the rocker member.
